UNITED STATES PATENT OFFICE.

GUSTAV A. BADER, OF ROCHESTER, NEW YORK.

SPECTACLE-MOUNTING.

1,031,228.

Specification of Letters Patent.

Patented July 2, 1912.

Application filed August 2, 1911. Serial No. 642,039.

To all whom it may concern:

Be it known that I, GUSTAV A. BADER, a citizen of the United States, and resident of Rochester, in the county of Monroe and State of New York, have invented certain new and useful Improvements in Spectacle-Mountings, of which the following is a specification.

This invention relates to mountings for spectacles or eyeglasses of the rimless type.

10 The object of the invention is to produce a simple, inexpensive, compact, and rigid construction for connecting the bridge of a spectacle or eyeglass-mounting with the portion of the mounting which is directly attached to 15 the lens, and to this end the invention consists in the construction hereinafter described, as it is defined in the succeeding claims.

In the accompanying drawings:—Figure 20 1 is a front-elevation, on a greatly enlarged scale, of a portion of a spectacle-mounting embodying the present invention, the drawing showing the lens-straps and one end of the bridge in vertical section; and Fig. 2 is 25 a perspective view of the same parts, with the end of the bridge detached from, but ready for connection with, the rest of the mounting.

In the drawings the inner end of one of 30 the lenses 3 is shown, together with one end of the bridge 4. These parts may be of any ordinary or suitable form, except that the extremity 5 of the bridge is horizontally disposed, as shown in Fig. 2.

35 The part of the mounting which is directly secured to the inner end of the lens consists of a member 6 which may conveniently be formed of sheet-metal, and which is bent into U-shape, in horizontal section, so as to 40 provide lens-clips 7 of ordinary form. These lens-clips are secured to the lens by means of a screw 8 in the ordinary manner.

The invention resides particularly in the manner in which the bridge is secured to the 45 member 6. To this end the latter is perforated or slotted so as to form a recess extending horizontally across the edge of the lens. The extremity 5 of the bridge is seated in this recess or slot and rigidly secured 50 therein. The bridge and the member 6 are preferably soldered together, but for additional security, and also to assist in the assembling of the mounting, the parts are formed to have an interlocking engagement. 55 To this end the upper and lower edges of the slot in the member 6 are beveled to form

tongues 9, and the extremity 5 of the bridge is provided with slots 10 in its upper and lower surfaces which interlock with the tongues 9. This arrangement permits the 60 extremity 5 to slide longitudinally into engagement with the member 6, but limits the parts to such endwise movement, thus greatly strengthening the construction. This interlocking engagement facilitates the 65 assemblage of the parts of the mounting, since it holds the parts temporarily in proper relative position while they are being soldered together.

In the drawings the slot in the member 6 70 is shown as extending into the lens-clips for the sake of lightness, but this is not essential to the invention. The usual lens-straps 11 are provided, these being conveniently formed integral with the other parts of the 75 member 6.

It will be noted that, owing to the formation of the slot in the member 6, the amount of metal comprised in the mounting is somewhat reduced, while at the same time the 80 construction is strengthened, since the area of the contacting surfaces between the parts is increased, thus affording greater security in the soldered joint. It is also a feature of value that when the extremity of the bridge 85 is thus inserted in the slot or recess, it lies substantially flush with the inner surface of the member 6, thus producing a neat and compact appearance.

While the construction just described is 90 designed particularly for use in spectacle-mountings, it will be obvious that it may also be applied to eyeglass-mountings of the type in which a rigid bridge is employed in connection with adjustable nose-clamps thereon, 95 and my invention is not, therefore, limited to use in spectacle-mountings alone.

I claim:—

1. In a spectacle-mounting, the combination of a sheet-metal member formed with a 100 central perforation and bent into U-shape in horizontal section so as to provide lens-clips adapted to embrace the inner end of the lens, and a bridge having its extremity horizontally disposed, said extremity being seated 105 and soldered in said perforation.

2. In a spectacle-mounting, the combination of a clip-member formed to embrace the inner end of the lens and provided with means for securing it thereto, said member 110 having a horizontal slot formed with upper and lower beveled edges, and a bridge hav-

ing its extremity horizontally disposed, said extremity being seated in said slot and having portions engaging and interlocking with said beveled edges.

5 3. In a spectacle-mounting, the combination of a clip-member formed to embrace the inner end of the lens and provided with means for securing it thereto, said member being perforated at its inner extremity to
10 form a recess extending horizontally across

the edge of the lens, and a bridge having its extremity horizontally disposed, said extremity being soldered in the perforation in the clip-member with its inner surface substantially flush with the inner surface of the 15 clip-member.

GUSTAV A. BADER.
